(57) **CLAIM**

The ornamental design for a flooring for building as shown and described.

DESCRIPTION

The patent or application file contains at least one drawing executed in color. Copies of this patent or patent application publication with color drawing(s) will be provided by the Office upon request and payment of the necessary fee.

FIG. 1 is a top plan view of a first embodiment of a flooring for building showing my new design;

FIG. 2 is a partial enlarged view of the top plan view of the first embodiment thereof;

FIG. 3 is a top plan view of a second embodiment thereof; and,

FIG. 4 is a partial enlarged view of the top plan view of the second embodiment thereof.

In the drawings, the broken lines represent portions of the article which form no part of the claimed design.

1 Claim, 4 Drawing Sheets
(4 of 4 Drawing Sheet(s) Filed in Color)
